CLAIM

The ornamental design for a display screen with graphical user interface as shown and described.

DESCRIPTION

FIG. 1 is a front view of a first embodiment of a display screen with graphical user interface showing our new design; and

FIG. 2 is a front view of a second embodiment of a display screen with graphical user interface showing our new design; and,

FIG. 3 is a front view of a third embodiment of a display screen with graphical user interface showing our new design.

The uneven broken lines illustrate the boundary of the claimed design and portions of a display screen and form no part of the claimed design. The remaining even-length broken lines illustrate portions of the graphical user interface and form no part of the claimed design. The broken line text forms no part of the claimed design.

1 Claim, 3 Drawing Sheets
